UNITED STATES PATENT OFFICE.

JAMES MEANS, OF BOSTON, MASSACHUSETTS.

DEVICE FOR LAUNCHING FLYING-MACHINES.

No. 922,713.

Specification of Letters Patent.

Patented May 25, 1909.

Application filed October 14, 1908. Serial No. 457,640.

To all whom it may concern:

Be it known that I, JAMES MEANS, a citizen of the United States, and a resident of Boston, in the county of Suffolk and State of Massachusetts, have invented a new and useful Improvement in Devices for Launching Flying-Machines, of which the following is a specification.

My invention relates to apparatus for launching flying machines of the aeroplane type wherein a certain high initial velocity in a direction opposite to that of the wind, imparted by means extraneous to the machine, is desirable for soaring.

My invention has special relation to the type of launching apparatus described in my application Serial No. 449,433, filed August 20, 1908, and its object is to provide means whereby the weight of such apparatus may be decreased in order to render the same more easily transportable.

It will be readily understood that the portability of such launching apparatus is quite essential to the use of flying machines in military and other operations, and to this end it is desirable that no one part of the apparatus shall be of greater size or weight than can conveniently be carried from place to place by the usual means employed for transporting military equipment.

It is obvious that in launching a flying-machine the maximum of power required is exerted for only a few seconds at the time of launching. It is also obvious that a motor capable of continuously exerting this maximum would be cumbersome in transportation on a military field. I therefore accomplish the desired result by availing myself of a small and easily transportable motor provided with attachments which enable it to exert as a maximum the cumulative effect of its action, in the manner hereinafter described.

With the foregoing object in view, my invention consists in means whereby the energy of a small prime-mover, such for example as a one-cylinder explosive engine, may be stored or accumulated for a relatively long period of time and then expended in a relatively short period of time, for example, the time required for launching a flying machine.

My invention embodies therefore a prime-mover having a potential energy storing device such as a flywheel, and means for in-

creasing, preferably progressively, the speed or effective weight, and therefore the momentum, of such device.

In the drawings which accompany and form a part of this specification, Figure 1 is a side view partly in section of my improved apparatus for launching flying-machines. Fig. 2 is an elevation of one embodiment of my energy accumulator. Fig. 3 is a vertical section taken on the line 3—3 of Fig. 2. Fig. 4 is an elevation partly in section of another embodiment of my energy accumulator.

In the drawings, 1 represents a revoluble table supported, preferably on ball bearings or other friction reducing devices, by the standards 2 and the journal 4, which affords a bearing for the axle 3 rigidly secured to said table. The upper floor of said table, carried by the uprights 5, supports the base 6 in such manner that the latter may be tilted at any desired angle with respect to said table. As shown in the drawings the base is pivoted at 7 to the standard 8 supported by the upper floor of said table, and although it will be understood that any convenient means may be employed for elevating one end of said base, the particular means disclosed herein consists, as shown, in the member 12 provided with the rack 16 with which the gear 14 engages. The base 6 rests upon a roller 13 journaled in the upper portion of the member 12, so that the operation of said gear by the crank 15 or other suitable means will serve to elevate the outer end of said base, retrograde motion being prevented by the pawl 18 coöperating with the teeth 17. Inasmuch as the tension of the endless cable 9, passing over and supported by the pulleys 10, the shafts of which have bearings in the journals 11, 11', will be varied when the base is tilted at an angle with respect to the table, I may provide means for shifting the position of the journal 11' so as to vary the tension of said cable in a direction to compensate that caused by said tilting. As shown, the means employed to accomplish this result consist in the screw 19 operated by the crank 20 and coöperating with the base of the journal 11' so as to move the latter which may be supported in the grooves 21.

It will be understood that the improvements about to be described may be used independently of the foregoing arrangement of revoluble table, tilting means, and cable.

tension-relieving means, although it will be found desirable in many instances to use the same conjointly.

By reference to my application above referred to it will be seen that when the pulley 10 is rotated by any suitable motor so that when the endless cable 9 has imparted to it a high velocity, a flying-machine or truck carrying the same may be given a corresponding velocity by clutch mechanism co-operating with the cable. No particular type of motor suitable for driving the cable was described in said application and I shall now describe with reference to Figs. 2, 3 and 4 of the drawings mechanism suitable for military transportation for giving the desired velocity to the said cable.

In Fig. 2, 22 represents the shaft carrying the pulley 10 and having bearings in the journals 11, 11'', said pulley being shown in side view and said shaft in section in Fig. 1, the line of the section being the line 1—1 in Fig. 2. 23 represents a flywheel which, as shown in Fig. 3, preferably is made in sections, herein shown as two in number, bolted together in the usual manner at 29 and 30. Although for convenience said flywheel is shown as consisting of two sections, it will be understood that a greater number of sections 30 may be and preferably will be employed. The object in using a sectional flywheel is of course to facilitate the transportation of the apparatus. 25 represents a small, easily transportable prime-mover, for example, a single-cylinder internal combustion engine. Arranged between the motor 25, and the shaft 22 to which are keyed the pulley 10 and flywheel 23 is the speed-changing device 24, which is bolted to the base 6 and which is operated by the lever 28 in the usual manner, and the friction clutch 26 which is operated by the lever 27. The speed-changing device may be of any suitable construction and inasmuch as such devices are well known and 45 the construction thereof constitutes no part of the present invention, I deem it unnecessary to further describe the same, except to say that preferably it should be capable of giving to the shaft 22 from three to five different speeds. While the friction clutch is not absolutely essential I prefer to use the same inasmuch as speed-changing devices are frequently injured in operation unless the motive power is disconnected from the 55 ingoing shaft thereof.

The operation of the apparatus above described is as follows: The speed-changer 24 is set by the lever 28 so that the shaft 22 will have the minimum speed, the motor is started and the friction clutch is closed, whereupon the flywheel 23 which may be too heavy to be rotated by the motor at a high rate of speed, will rotate slowly. As soon as said flywheel has acquired its maximum 65 velocity with the speed-changer set for least

speed, the friction clutch is opened and the speed-changer set for the next higher speed, and so on progressively until the flywheel is rotating at the maximum speed attainable with the speed-changer set for the highest 70 speed. In this way a large amount of energy may be stored up in said flywheel during the relatively long period of time required to bring the same to full speed, and such full speed having been acquired, the device is in 75 condition to expend said energy during the relatively short period of time, at most a few seconds, required for launching a flying machine. It is of course obvious that by the employment of a much larger prime-mover an even heavier flywheel than the one above described could be brought to even 80 higher velocity, but such an arrangement would be impracticable because of its lack of portability. However by means of the apparatus shown in Fig. 2 it is possible to employ a flywheel which is so heavy that the motor 25 would not be able to turn the same over were the speed-changer set for highest speed, or if it were directly connected, but 85 which may be brought progressively up to the highest desirable speed by the procedure above outlined.

In Fig. 4 I have shown another apparatus for accomplishing the result above set forth. 90 In the apparatus shown in Fig. 2 the momentum of the flywheel is increased by progressively increasing the speed thereof, and in that shown in Fig. 4 the momentum is increased by progressively increasing the 100 weight of the mass rotating with the shaft 22. In Fig. 4 the pulley 10, which is rigidly secured to the shaft 22, may be made heavy enough to perform the functions of a flywheel, and one or more auxiliary flywheels 105 31, 32, and 33 may be associated with said pulley in any suitable manner so that progressively one or more may be secured to and caused to rotate with the same. In that particular embodiment of my invention 110 shown in Fig. 4 the said flywheels are secured to the sleeves 310, 320, 330, which are provided with outer flanges 311, 321, 331, with which the levers 34, 35, 36 respectively co-operate. The pulley 10 having been brought to full speed by the motor 25, the lower end of the lever 34, which may be pivoted to a frame 342, is forced over the spring-pressed latch 38 by the handle 343 or other suitable means, so that the upper end 115 of said lever, which may be provided with a wheel 341 will force the sleeve 310 forward and thereby secure the flywheel 31 by friction or otherwise to the pulley 10. The flywheel 31 will thereupon acquire a speed 120 practically the same as that of the pulley 10, whereupon, by means of the levers 35 and 36 the flywheel 32 may be secured to the flywheel 31 and finally the flywheel 33 may be 125 caused to rotate with the pulley 10 and fly- 130

wheels 31 and 32. When the entire rotating mass, which is now secured to the shaft 22, has acquired the maximum speed attainable by the motor 25, the apparatus is in condition for launching a flying-machine.

It will be understood that the flywheels 31, 32 and 33 may be so chosen that their combined weights added to that of the pulley 10 would be so great as to prevent the starting 10 of the motor 25, and yet by the procedure above outlined of first starting the motor with a light load and progressively increasing the same for a relatively long period of time, a large amount of energy may be accumulated 15 and then expended during the few seconds required for launching a flying-machine.

While for the purpose of more fully disclosing my invention I have described in detail 20 two specific embodiments thereof, it will be understood that I do not limit myself to said embodiments inasmuch as many modifications may be made therein without departing from the principal thereof, which 25 briefly stated, consists in progressively increasing the momentum of a moving mass during a relatively long period of time, by progressively increasing either the speed or the weight of said mass, and then expending 30 accumulated energy of said mass during a relatively short period of time.

I claim:

1. In a device for launching flying-machines, the combination with a prime mover 35 and an endless cable of a shaft operatively associated with said cable for actuating the same, a flywheel secured to and rotating with said shaft, and means for increasing the momentum of said flywheel during the rotation thereof without increasing the speed of said prime mover.

2. In a device for launching flying-machines, the combination with a revolute table 45 a prime mover and an endless cable supported thereby of a shaft operatively associated with said cable for actuating the same, a flywheel secured to and rotating with said shaft, and means for increasing the momentum of said flywheel during the rotation thereof without increasing the speed of said prime mover.

3. In a device for launching flying-machines, the combination with an endless cable 55 of a shaft operatively associated with said cable for actuating the same, a sectional flywheel secured to and rotating with said shaft, and means for increasing the momentum of said flywheel during the rotation thereof.

60 4. In a device for launching flying-machines, the combination with an endless ca-

ble of a shaft operatively associated with said cable for actuating the same, a flywheel secured to and rotating with said shaft and means for progressively increasing the momentum of said flywheel during the rotation thereof.

5. In a device for launching flying-machines, the combination with an endless cable 70 of a shaft operatively associated therewith for actuating the same, a sectional flywheel secured to and rotating with said shaft, and means for progressively increasing the momentum of said flywheel during the rotation thereof.

6. In a device for launching flying-machines, the combination with an endless cable, 75 of a shaft operatively associated with said cable for actuating the same, a flywheel secured to and rotating with said shaft, and means for increasing the speed and thereby the momentum of said flywheel during the rotation thereof.

7. In a device for launching flying-machines, the combination with an endless cable, 80 of a shaft operatively associated with said cable for actuating the same, a flywheel secured to and rotating with said shaft, and means for progressively increasing the speed and thereby the momentum of said flywheel 85 during the rotation thereof.

8. In a device for launching flying-machines, the combination with an endless cable, 90 of a prime-mover associated therewith, a flywheel, and a speed-changing device arranged between said prime-mover and said flywheel.

9. In a device for launching flying-machines, the combination with an endless cable, 95 of a prime-mover associated therewith, a flywheel, and a speed-changing device and friction clutch arranged between said prime-mover and said flywheel.

10. In a device for launching flying-machines, a revolute table, a base pivotally 100 supported thereby and normally parallel therewith and means for tilting said base at an angle to said table.

11. In a device for launching flying-machines, a revolute table, a base pivotally 110 supported thereby and normally parallel therewith, means for tilting said base at an angle to said table, an endless cable parallel with said base and means for varying the tension on said cable when said base is so tilted.

In testimony whereof, I have hereunto 115 subscribed my name this 13th day of Oct., 1908.

JAMES MEANS.
